UNITED STATES PATENT OFFICE.

WILFRID FRANCIS RAVENOR, OF VANCOUVER, BRITISH COLUMBIA, CANADA.

OIL BURNER.

Application filed December 17, 1921. Serial No. 523,194.

To all whom it may concern:

Be it known that I, WILFRID FRANCIS RAVENOR, a subject of the King of Great Britain, residing at the city of Vancouver, in the Province of British Columbia, Canada, have invented certain new and useful Improvements in Oil Burners, of which the following is a specification.

My invention relates to improvements in oil burners, and the object of my invention is to devise an oil burner which is simple in construction and capable of being manufactured at a comparatively low cost, which is highly efficient in operation and does not backfire nor readily choke, since carbon deposit in the generator is prevented, and in which the possibility of leakage when cold is eliminated. A further object is to provide a burner of this character which is air cooled throughout and in which the oil is practically boiled in bulk before entering the generator proper, while a still further object is to devise an oil burner capable of being formed of separate sections bolted together and thus permit of burners of different lengths being easily, quickly, and cheaply assembled ready for use.

I attain these objects by the construction illustrated in the accompanying drawings in which—

Fig. 1 is a side elevation of a burner.

Fig. 2 is a longitudinal sectional elevation of the same.

Fig. 3 is a plan view.

Fig. 4 is a cross section taken through a burner section, showing the air passages.

Fig. 5 is an outside view of a burner section, looking on the end.

Fig. 6 is a detail view of the gas valve.

Fig. 7 is an enlarged fragmentary view showing the valved end of the fuel injection pipe, in cross section.

Similar figures of reference indicate similar parts throughout the several views.

The burner proper, indicated by the numeral 1, consists of a number of sections bolted or otherwise secured together, and as these sections are similar to one another it will be sufficient, therefore, to describe one of them specifically. Such a section is shown in Figs. 4 and 5 and consists of a thin box-like casing 2, substantially rectangular in cross section, although it may be any other suitable form, through which extends centrally an opening 3 on each side

of which and separated therefrom by walls 4 and 5 are air passages 6 and 7, these passages extending vertically through the section from the bottom to the top of the same and being widened at the top end, as at 8 in Fig. 4. The upper edge of the section intermediate its width is depressed to form a concave depression 9, while through the solid portion of the section above and below the opening 3 respectively extend bolt holes 10—11 and 12—13, as shown more particularly in Fig. 5. Thus, when a number of sections similar to that described in the foregoing are placed together face to face, separated, however, by upper and lower wires 14 and 15 of small diameter which are first of all inserted between them, they may be all secured together by means of the bolts 16—17 and 18—19 passed through the bolt holes 10—11 and 12—13 so that a complete burner 1 is formed consisting of a plurality of connected sections and having an interior gas chamber, indicated generally by the numeral 20, formed by the openings 3 of the independent sections, which gas chamber is in communication with the atmosphere through the slits 21 provided between the sections through the insertion of the spacing wires 14 and 15 therebetween. As the concave depressions 9 of the respective assembled sections all register one with the other the complete burner is therefore provided in its upper surface with a substantially concave trough, indicated generally by the numeral 22 in Fig. 3, which trough extends throughout the whole length of the burner, and due to the provision of the vertical air passages 6 and 7 in each section the entire burner is air cooled throughout.

It should be mentioned here that each end section of a complete burner so formed has its outer face solid, as at 23 and 24 in Fig. 2, the end section remote from the fuel supply pipe being provided, however, with a funnel shaped member 25 the lower end of which extends through the wall 24 of the section into the gas chamber 20 and through which funnel extends vertically a valve stem 26 the lower end of which is connected to a suitably mounted valve operating lever 27 used for opening and closing the valve provided on the upper end of the stem, as will be more fully described hereinafter.

The generator, indicated generally by the

numeral 28, consists of a pipe 29 mounted centrally of the trough 22 and supported in close proximity to the bottom of the trough by a vertically extending bracket 30 secured to the end section wall 23, which pipe extends longitudinally of the burner and projects beyond it at its opposite ends, and at the end remote from the fuel supply pipe 31 the pipe is closed while its opposite end is doubled over upwardly to form a return bend 32 and extended to provide a continuation of the lower pipe, this upper pipe, indicated by the numeral 33, extending about half the length of the burner and having its end closed by a cap 34 provided with a threaded central bore 35 through which extends a correspondingly threaded stem 36 the inner end of which is formed as a valve 37, of mitred or other construction. This valve 37 operates with a valve seat 38 formed in the end of the fuel injection pipe 39, which pipe passes centrally through the upper pipe 33 of the generator and extends exteriorly of it at the end opposite to the capped end, as at 28 40, so that it may be connected to the fuel supply pipe 31.

The lower generator pipe 29 is filled for the greater part of its length from the return bend end with particles 41 of absorbent material such as burnt fireclay, and adjacent its closed end and centrally of the upper end of the funnel 25 an apertured boss 42 is formed extending interiorly and exteriorly of the pipe, as shown in Fig. 2, 35 the aperture of which is fitted with a sleeve, indicated by the numeral 43 in Fig. 6, having a circular parallel bore which forms a valve seat 44 adapted to co-act with a tapered squared end 45 provided on the upper end 40 of the valve stem 26 and which end 45 acts as a valve to regulate the passage of gas through the aperture of the boss 42 when raised or lowered by the operation of the lever 27, or any other equivalent device.

45 The generator pipe 29, and 33, is preferably exteriorly threaded, thus thinning the pipe walls so that the heat may the more readily pass therethrough without excessively weakening the pipe and at the same time 50 providing a much greater heating surface than if the pipe were plain and unthreaded although it may be made so, if desired.

46 indicates a hood enclosing the funnel 25, which hood is, however, open at the bottom, as shown in Fig. 2.

The manner in which the burner operates may be briefly described, it being understood that the device when in use is placed in the firebox of a stove, fireplace, boiler, or the like. The generator is first of all preheated by burning a small quantity of fuel in the trough 22, which fuel may be carried by wick, asbestos, or such like material. When the generator is sufficiently hot the 60 fuel is admitted into the generator from the

fuel pipe 31 and, on the valve 45 being opened the requisite amount, passes in the form of combustible gas into the funnel 25 and the gas chamber 20 so that it may be lighted at the slits 21, continuing then to 70 burn as long as the supply of fuel from the pipe 31 is maintained.

It should be particularly noted that, when the burner is cold, the valve 37 formed on one end of the stem 36 is permanently tightly seated on the valve 38 formed in the end of the fuel injection pipe 39. However, as the fuel injection pipe is colder than the pipe 33 and cap 34 when the burner is in use, the cap will expand to a greater extent 80 than the pipe 39 so that the valve 37 will be automatically opened by such expansion sufficiently to permit the passage of fuel therethrough into the pipe 29, automatically closing however by the contraction of the cap 85 as the burner cools. The particles of fireclay 41 act as a retarding absorbent wick and also prevent carbon deposit in the pipe 29, the deposit of carbon being further prevented by projecting the return bend 32 beyond the end of the burner so that this part 90 of the generator is maintained comparatively cool and scorching of the oil is eliminated.

It will be noted further that the needle valve 45 opens externally, that is, it opens 95 away from the pressure so that the gas issues through the aperture or seat 44 with the most efficient velocity of jet, which is not decreased as the valve closes, as is the case where the valve opens internally or on the 100 pressure side of the orifice, and further, the valve 45 being square in cross section instead of the circular construction usually found in burners at the present time, it seats itself evenly when closed all around the circular seat so that the flow of gas is even all around the valve stem, thus eliminating the possibility of the valve pressing on one side only of the seat and allowing the gas 105 to escape at the other side, as frequently happens where circular type needle valves 110 are employed.

The provision of the vertical air passages in each burner section, besides ensuring the air cooling of the burner, also provides an 115 effective means of distributing the heat, since the air draught travelling through the passages on its way to the chimney conveys the heat units from the burner through the flues and around the oven.

120 From the foregoing it will be seen that I have provided an oil burner which is simple in construction and highly efficient in operation.

What I claim as my invention is:

125 1. An oil burner comprising a plurality of centrally apertured sections connected together with the apertures of the sections in registration whereby a chamber is formed in the burner interior, each said section be- 130

- ing provided with air passages on each side of its apertures, means for spacing the connected sections from each other, and means for supplying gas to the chamber.
5. 2. An oil burner comprising a plurality of centrally apertured spaced sections connected together with the apertures of the sections in registration whereby a chamber is formed in the burner interior, an externally threaded generator pipe extending longitudinally of the burner in proximity to its upper surface having a valved orifice adjacent one end, a funnel shaped nozzle the upper end of which is concentric with the said orifice while its lower end extends into the said chamber, a needle valve partially closing said orifice having its stem extending vertically through the funnel, and means for supplying fuel to the said generator pipe.
10. 3. An oil burner comprising a plurality of centrally apertured spaced sections connected together with the apertures of the sections in registration whereby a chamber is formed in the burner interior, an externally threaded generator pipe extending longitudinally of the burner in proximity to its upper surface having an orifice adjacent one end provided with a sleeve having a round bore forming a valve seat, a funnel shaped nozzle the upper end of which is concentric with the said seat while its lower end extends into the said chamber, a valve stem extending vertically through said funnel having its upper end tapered and squared to form a valve adapted to co-act with the said round seat for regulating the gas flow through the orifice, means for operating said valve stem, and means for supplying fuel to the generator pipe.
15. 4. An oil burner comprising a plurality of centrally apertured spaced sections connected together with the apertures of the sections in registration whereby a chamber is formed in the burner interior, an externally threaded generator pipe extending longitudinally of the burner in proximity to its upper surface having a valved orifice adjacent one end and a fuel inlet at its opposite end, particles of a catalytic agent within said generator pipe between the fuel inlet and the orifice, and means for directing gas discharged from the orifice into the chamber.
20. 5. An oil burner comprising a plurality of centrally apertured spaced sections connected together with the apertures of the sections in registration whereby a chamber is formed in the burner interior, an externally threaded generator pipe extending longitudinally of the burner in proximity to its upper surface having a valved orifice adjacent one end its opposite end being doubled over on itself and extended intermediate the length of the burner, the end of the said
- extended portion being capped, a fuel injection pipe within said extended portion having its inner end extending adjacent said cap and formed as a valve seat, a valve stem extending through said cap having its inner end formed as a valve and seated on said seat, and means for directing gas discharged from the generator pipe orifice into the burner chamber.
25. 6. An oil burner comprising a plurality of centrally apertured sections each having a concave depression in its upper edge connected together with the apertures and depressions of the sections in registration whereby a chamber is formed in the burner interior and a longitudinally extending concave trough is formed in the burner upper surface, each said section being provided with air passages on each side of its aperture and the opposite end sections of the burner each having a solid outer wall so that the chamber is closed as to its opposite ends, wire distance pieces inserted between each section above and below the section aperture whereby slits extending from the chamber exteriorly of the burner are provided, an externally threaded generator pipe extending longitudinally of the burner within said trough having an orifice adjacent one end provided with a sleeve having a round bore forming a valve seat and being doubled over on itself at its opposite end and extended intermediate the length of the burner, the end of the extended portion being capped, a fuel injection pipe within the said extended portion having its inner end extending adjacent said cap and formed as a valve seat, a valve stem extending through said cap having its inner end formed as a valve and seated on said seat, a funnel shaped nozzle having its upper end disposed under and concentric with the generator pipe orifice and its lower end extending into the burner chamber, and a valve stem extending vertically through said funnel having its upper end tapered and squared to form a valve co-acting with the said round seat of the orifice, to partially close the same.
30. 7. In an oil burner, a generator comprising a main pipe member having a valved orifice adjacent one end and doubled over on itself at the opposite end and extended intermediate the length of the main pipe member, the end of said extension being closed, a central fuel injection pipe within said extension having its inner end disposed adjacent said closed end and formed as a valve seat its opposite end being adapted for connection to a fuel supply, and a valve stem extending through the closed end having its inner end formed as a valve co-acting with said valve seat to open and close the same.
35. 8. In an oil burner, a generator comprising

ing an externally threaded main pipe member having a valved orifice adjacent one end and doubled over on itself at the opposite end and extended intermediate the length of the main pipe member, said extension being also externally threaded and having its end closed, a central fuel injection pipe within said extension having its inner end disposed adjacent said closed end and formed as a valve seat its opposite end being adapted for connection to a fuel supply, and a valve stem extending through the closed end having its inner end formed as a valve co-acting with said valve seat to open and close the same.

9. In an oil burner, a generator comprising a main pipe member having a valved orifice adjacent one end and doubled over on itself at its opposite end and extended intermediate the length of the main pipe member, the end of said extension being closed by a cap, a central fuel injection pipe within said extension having its inner end disposed adjacent said cap and formed as a valve seat its opposite end being adapted for connection to a fuel supply, and a valve stem extending through the cap having its inner end formed as a valve co-acting with said valve seat, said valve being adapted to seat and unseat itself automatically through the contraction and expansion respectively of the said capped extension.

10. In an oil burner, a main generator pipe, an auxiliary generator pipe, an internal fuel injection pipe disposed above the main pipe and extending centrally into the auxiliary generator pipe, and an elbow connecting said auxiliary generator pipe with the main generator pipe at one end and act-

ing as a return and being projected beyond the end of said burner.

11. In an oil burner, a main generator pipe, an auxiliary generator pipe, an internal fuel injection pipe disposed above the main pipe and extending centrally into the auxiliary generator pipe, an elbow connecting said auxiliary generator pipe with the main generator pipe at one end and acting as a return and being projected beyond the end of said burner, and a catalytic agent within the said main generator pipe.

12. In an oil burner, an externally threaded main generator pipe, an externally threaded auxiliary generator pipe disposed above the main pipe in communication therewith and into which extends centrally an internal fuel injection pipe.

13. In an oil burner, an externally threaded main generator pipe, an externally threaded auxiliary generator pipe disposed above the main pipe communicating therewith at one end and capped at its opposite end, an internal fuel injection pipe extending centrally into the auxiliary pipe having its inner end formed as a valve seat and disposed adjacent the said capped end, and a valve carried by said cap seated in the valved end of the said injection pipe.

14. In a sectional oil burner, a section consisting of a thin box-like casing having a central aperture and air passages extending vertically through the casing on each side of the aperture.

In testimony whereof I affix my signature at the city of Vancouver, B. C., Canada, this 30th day of November, 1921.

WILFRID FRANCIS RAVENOR.
